DESIGN FOR AN AUTOMATIC DIAL AND NIGHT LIGHT ATTACHMENT FOR TELEPHONES

Harry Katz, Cincinnati, Ohio

Application December 17, 1948, Serial No. 150,215

Term of patent 14 years

(Cl. D26—14)

To all whom it may concern:

Be it known that I, Harry Katz, a citizen of the United States, residing at Cincinnati, in the county of Hamilton and State of Ohio, have invented a new, original, and ornamental Design for an Automatic Dial and Night Light Attachment for Telephones, of which the following is a specification, reference being had to the accompanying drawings, forming part thereof.

Fig. 1 is a perspective view of an automatic dial and night light attachment for telephones, showing my new design.

Fig. 2 is a perspective view of the other side of Fig. 1 taken from the opposite end thereof.

I claim:

The ornamental design for an automatic dial and night light attachment for telephones, as shown.

HARRY KATZ.
